(57) CLAIM

We claim the ornamental design for the hygiene products tray, as shown and described.

DESCRIPTION

FIG. 1 is a perspective view showing our new design of a hygiene products tray;

FIG. 2 is a front side view of the hygiene products tray;

FIG. 3 is a right side view of the hygiene products tray;

FIG. 4 is a back view of the hygiene products tray;

FIG. 5 is a left side view of the hygiene products tray;

FIG. 6 is a top view of the hygiene products tray;

FIG. 7 is a bottom view of the hygiene products tray;

FIG. 8 is another perspective view of the hygiene products tray; and,

FIG. 9 is yet another perspective view of the hygiene products tray.

In the drawings, any broken lines shown in FIGS. 1-9 depict portions of the design that form no part of the claim.
